UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

HOPPER-CAR STRUCTURE.

Application filed December 19, 1925. Serial No. 76,479.

My invention relates to improvements in the construction of the underframe and adjacent superstructure of railway hopper cars and consists in the provision of frame elements, bearing brackets, reinforcing braces, elements for the mounting of superstructure framing and apparatus, and other details referred to below.

The object of my invention is to provide an economical rigid structure, preferably consisting substantially of a one-piece casting provided with integral extensions and flanges for performing various functions heretofore fulfilled by separate pieces applied to the car framing or fulfilled by a more cumbersome or inconvenient structure.

More specifically I desire to eliminate the heavy and unnecessary corners of the underframe of a car of the type referred to, such as the corners shown in my copending application Serial No. 576,527 filed July 21, 1922; to provide for the attachment of end posts direct to the striking plate of the underframe; to provide for truck bearings extending beyond the body of the underframe; and to properly brace these bearings from the body and to adapt them for the mounting of superstructure posts, and to receive and take care of lifting stresses produced by application of jacks or slings at their extensions. I also desire to adapt an underframe of the type referred to for the application of brake levers or similar mechanism without the necessity of attaching separate brackets, etc., to provide for the direct application of dumping doors to the car sills with accuracy and without the necessity of extensive machine-work on the sills and to similarly apply floor supporting brackets to the underframe with accuracy and without extensive machine-work.

I also desire to brace the end floors of the hopper car by means of suitably disposed flanges on the underframe.

Various other detailed objects of my invention will appear in the description below.

In the accompanying drawings illustrating a selected embodiment of my invention—

Figure 1 is a top view of my improved underframe.

Figure 2 is a side elevation of the same.

Figure 3 is a longitudinal vertical section taken on line 3—3 of Figure 1.

Figures 4 and 5 are vertical transverse sections on line 4—4 and 5—5 of Figure 1.

Figure 6 is an end view of one-half of the structure.

Figure 7 is a detail vertical section on line 7—7 of Figure 1.

Figures 8 and 9 are transverse sections on line 8—8 and 9—9 of Figure 1, Figure 9 showing the dumping doors applied to the underframe.

Figure 10 is a vertical transverse section on line 10—10 of Figure 6.

Figure 11 is a horizontal section taken on line 11—11 of Figure 6.

The main portion of the structure shown consists of side sills 1, draft sills 2, and diagonal sills 3. The side sills terminate a substantial distance from the end of the car and near their ends are connected to each other by straight transverse members 4 extending between the lower portions of the side sills and by arcuate members 5 extending between the upper portions of the side sills and forming with the upper portions of the draft sills 2 and diagonal sills 3 and other connecting elements to be referred to later a substantially horizontal platform-forming portion of the underframe.

Extending outwardly from the diagonal sills 3 are brackets 6, the lower portions of which are provided with bearings 7 which are adapted to rest upon the side frames of the type of truck illustrated in Patent No. 995,560, issued June 20, 1911 to H. M. Pflager and more particularly described and claimed in the copending Pflager application Serial Number 34,706 filed June 3, 1925. The outer ends of these brackets are braced from the ends of the side sills 1 by connections 8, and brackets 6 and connections 8 terminate in a face provided for the attachment of the car corner posts 9.

The outer ends of brackets 6 and connections 8 are provided with a flat undersurface 10 to receive a jack or block whereby the car may be lifted. The lower face of connection 8 is recessed as indicated at 11 (Figure 2) to provide a notch for engaging chains or slings whereby the car may be raised. Adjacent jacking surfaces 10 and recesses 11, the frame is provided with bosses 31 and 32 to which superstructure posts 9 and post brackets 33 and operating mechanism (not shown) may be attached,

respectively, and the lifting forces will be applied at points best adapted to receive and transmit the resulting stresses.

A portion of the load on each diagonal sill 3 is transferred to the draft sill by transverse members 12 which are positioned approximately midway of the ends of the diagonal sills. It will be noted that one of these members 12 is bifurcated to provide a space 13 into which the operating gear wheel 14 of the door dumping mechanism may project. The arrangement, however, is such that the same degree of load stresses may be transferred by the bifurcated member 12 as by the other members 12.

A connection 12^a extends between the draft sills 2 at the point where members 12 connect with the draft sills. The lower portion of connection 12^a includes a horizontal section 12^b with upturned flanges 12^c and 12^d at front and rear, respectively. Front flange 12^c is curved rearwardly to accommodate the inner end of the draft gear which may be applied to the underframe.

Brackets 6, member 12 and connection 12^a form a bolster-like member extending roughly in an arc between the bearings 7 where the underframe is pivoted to its truck, thereby providing a continuous member, having an upper compression element and a lower tension element, extending transversely of the underframe, but adapting the underframe to have its trucks located nearer to the end of the underframe than would be the case with the ordinary bolster or any straight transverse member such as shown in my copending underframe application Serial Number 77,928, filed December 28, 1925.

The novel features included in the side sill structure are the provision of bosses or pads having finished surfaces for the application of door hinge elements and inclined side floor supporting brackets. As indicated in Figure 9, each side sill comprises a vertical flange 14 and inwardly extending horizontal flanges 15 and 16 at the top and bottom, respectively, of said vertical flange. It will be noted that the upper flange 15 extends inwardly from the side of the car a greater distance than the lower flange and is preferably provided with a depending rib 17 at its inner end.

At intervals along flange 15 and projecting from its upper and lower surfaces are bosses 18 each having a restricted lower face adapted to be machined and to which the eye bolts 19 forming part of the door hinge may be applied. The nuts for these eye bolts are seated upon the opposite upper boss faces. By means of this arrangement, the doors may be hinged directly to the side sills and this may be done without machining all along the sill. The shape of the side sill is such that the aligned faces

of all the bosses on each sill may be machined in a single operation and the door may be applied or removed from beneath the sill as desired and at the same time the door securing nuts 20 may be applied and removed from their respective eye bolts 19 from above. This greatly facilitates assembly and disassembly of the car door and underframe.

Along the outer face of the side sill vertical flange 14, are pads 21 which project from the body of the sill and may be machined to have applied thereto the brackets 22. These brackets which are more clearly detailed and described in my copending application, Serial Number 67,828, filed November 9, 1925, support the inclined side floors of the hopper from the side as well as the top of the side sill.

As indicated in Figures 1 and 5 the platform forming portion of the underframe is provided with downwardly depending arms 23, preferably formed integrally with the platform and at their lower ends provided with integral fulcrums for inclined brake levers or other similar operating mechanism. The adjacent draft sill 2 is recessed to accommodate mechanism projecting therethrough and arms 23 provide means for mounting levers abreast of the transverse opening in draft sill 2. Each of the draft sills has a lower horizontal flange 24 (Figure 5) and at the inner ends of the draft sills these flanges 24 merge into a transverse flange 25 which forms a reinforcement for the lower end of the hopper end floor and extends across the latter to the side sills 1.

The draft sills 2 extend a short distance beyond the point where diagonal sills 3 merge with the draft sills, thus providing an integral striking plate having parallel side faces 26 to which the end posts 27 may be secured. The sides of the striking plate portion of the underframe are connected by an integral cross member 28 which is channel-shaped in cross section with its web horizontal and its flanges depending. This member is adapted to have a channel-shaped wear plate 29 (Figure 11) fitted over it and when wear plate 29 is in position and is supporting a coupler shank, the weight of the coupler and the interengaging flanges of the plate and cross member 28 will retain the wear plate in position.

The flanges of member 28 are deepest intermediate their ends for additional strength.

The rear flange of plate 29 is cut away near each end as indicated at 30 in Figure 11 and thereby provides a notch adapted to receive the forward end of the coupler yoke Y. This permits greater travel of the yoke and coupler than would be possible otherwise unless the draft sill were lengthened.

The front faces of the draft sills are pro-

vided with openings 34 through which riveting tools or wrenches may be inserted to drive rivets or hold bolts connecting the sides of the draft sill and end posts 27. The lower flange of the side sills have openings 35 and 35^a to permit access to the inner face of the sill behind pads 31 and 21 for a similar purpose.

Obviously, many of the details of my invention might be varied without departing from the spirit thereof and I contemplate all such modifications as fall within the scope of the following claims.

I claim:

1. In a car underframe, a horizontal portion, a vertical sill beneath said portion and provided with a transverse opening for brake or similar mechanism, and elements formed integrally with said horizontal portion depending therefrom to provide mechanism mountings abreast of said openings.

2. In a car underframe, draft sills extending to the end of the underframe, side sills, diagonal sills connecting said side sills with points on said draft sills spaced from the outer ends of the latter, said draft sill ends having surfaces for the attachment of end posts in front of said diagonal sills.

3. In a car framing, a striking plate, side sills, diagonal sills extending inwardly and longitudinally of the underframe from the ends of said side sills to the end of the underframe at a point spaced from the face of said striking plate, and an end post connected to the side of the striking plate in front of the end of said diagonal sill.

4. In a car underframe, side sills, diagonal sills extending inwardly and longitudinally of the underframe from the ends of said side sills, and truck bearing supporting brackets extending outwardly from said diagonal sills.

5. In a car underframe, side sills, diagonal sills extending inwardly and longitudinally of the underframe from the ends of said side sills, and truck bearing supporting brackets extending outwardly from said diagonal sills and connected to the ends of said side sills independently of said diagonal sills.

6. In a car underframe, draft sills, side sills, diagonal sills connecting the forward portion of said draft sills to said side sills, and truck bearing brackets extending outwardly from said diagonal sills and toward the outer end of the underframe.

7. In a one-piece casting comprising a car underframe, draft sills, side sills, diagonal sills connecting said sills, and members extending outwardly from said diagonal sills and carrying truck bearing engaging elements.

8. In a car underframe, draft sills, side sills, diagonal sills connecting said draft and side sills, and brackets on said diagonal sills

extending outwardly therefrom and carrying truck engaging bearings.

9. In a car underframe, side sills, diagonal sills extending inwardly and longitudinally of the underframe from the ends of said side sills, and brackets extending outwardly from said diagonal sills to the side of the car and adapted to support posts for the car superstructure.

10. In a hopper car, side sills, diagonal sills extending inwardly and longitudinally of the underframe from the ends of said side sills, brackets extending outwardly from said diagonal sills to the side of the car, and corner posts connected to said brackets and extending upwardly therefrom.

11. In a one-piece casting comprising a car underframe, draft sills, side sills, diagonal sills connecting said sills, members extending outwardly from said diagonal members and carrying truck bearing elements, and braces extending from the ends of said side sills and connecting with the outer ends of said members.

12. In a car underframe, a side sill, a diagonal sill extending inwardly from said side sill toward the end of the car, a bracket extending outwardly from said diagonal sill, an element extending longitudinally from the end of said side sill, said element and bracket uniting to form a support and a brace for a car corner post.

13. In a car underframe, a side sill, a diagonal sill extending inwardly from the end of said side sill, a brace extending outwardly from the end of said side sill and adapted to support a body corner post at its outer end, a depending flange along said brace, and a lug on said flange near the outer end thereof for positioning a chain hook or sling for raising the underframe.

14. In a car underframe, a side sill, a diagonal sill extending inwardly from the end of said side sill toward the car end, a bracket extending outwardly from said diagonal sill and provided with a bearing for the car truck, and a projection beyond said bearing including a jacking surface.

15. In a hopper car, a side sill, a diagonal sill extending inwardly from the end of said side sill toward the car end, a bracket extending outwardly from said diagonal sill and provided with a bearing for the car truck, a projection beyond said bearing including a jacking surface, and a corner post having its lower end secured to said projection.

16. In an underframe for a dumping car, a draft sill, a diagonal sill, a bearing for the car truck carried by said diagonal sill, and a member for transferring a portion of the load on said bearing and diagonal sill to said draft sill, said member being bifurcated to accommodate dumping mechanism below the top of said underframe.

17. In an underframe for cars with dumping doors, a sill, pads at intervals along said sill projecting beyond the body of said sill, each affording a restricted individual mounting surface for a door hinge element.
18. A one-piece casting comprising an underframe for cars with dumping doors, said casting including a sill adjacent to the door opening, and bosses at intervals along said sill and projecting therefrom and having machined surfaces in a common plane.
19. In an underframe casting for cars with dumping doors, a sill member having a vertical web and laterally extending horizontal flanges, the upper of which flanges is wider than the lower, and integral bosses along the lower face of said upper flange within the edge of said lower flange for attachment with door hinge elements applicable and removable from below said sill.
20. In a hopper car underframe, a side sill with a flange, elements on one side of said flange for seating door hinge members, and elements on the other side of said flange for seating-retaining devices for said hinge members.
21. In a hopper car underframe, side sills, pads projecting beyond the outer faces of said sills at intervals for the application of members for supporting a hopper side floor.
22. In a one-piece casting forming a hopper car underframe, a side sill, and bosses of restricted area at intervals along the outer face of said sill and projecting therefrom and having machined surfaces for the application of floor supporting brackets.
23. In a hopper car, draft sills, lower flanges thereon, an inclined floor extending below said draft sills, said flanges extending along the rear face of said floor to reinforce the same.
24. A one-piece casting comprising a hopper car underframe, and including flanged draft sills, and supports for the lower ends of the hopper end floor, the flanges on said draft sills being continued transversely of the car along said supports.
25. A one-piece casting comprising a hopper car underframe and including side sills, flanged draft sills and supports for the lower ends of the hopper end floors, the flanges on said draft sills being continued transversely of the car along said supports to said side sills.
26. In a car underframe, draft sills, an integral striking plate and an integral coupler carrier extending transversely of said sills and which is channel-shape in cross section with its coupler supporting web horizontal and flanges depending.
27. In a car underframe, draft sills, an integral striking plate and an integral coupler carrier extending transversely of said sills and which is channel-shape in cross section with its coupler supporting web horizontal and flanges depending.
28. In a car underframe, an integral striking plate with an integral coupler carrier which is channel-shape in cross section with its web horizontal and its flanges depending and deepest intermediate their ends.
29. In a car underframe, an integral striking plate with an integral coupler carrier which is channel-shape in cross section with its web horizontal and flanges depending, and a removable channel-shaped wear plate fitting over said carrier, said wear plate having the ends of its inner flanges cut away to accommodate forward movement of a draft yoke for a coupler resting on said wear plate.
30. In a car underframe, a side sill, a diagonal sill extending inwardly from the end of said side sill toward the car end, a bracket extending outwardly from said diagonal sill and provided with a bearing for the car truck, and a projection beyond said bearing including a jacking surface, and adjacent pads for attaching superstructure posts.
31. In a car underframe, a side sill, a diagonal sill extending inwardly from the end of said side sill toward the car end, a bracket extending outwardly from said diagonal sill and provided with a bearing for the car truck, a projection beyond said bearing including a jacking surface, and adjacent pads for attaching operating mechanism.
32. In a car underframe, draft sills projecting at the end of the car and each forming a hollow portion with a side face for attaching a superstructure post, the end face of said portion being provided with an opening to permit access to the inner side of said face to facilitate assembly of a post therewith.
33. In a car underframe, a cast sill member forming a box-like section with an exterior pad for posts or the like, the lower face of said portion being provided with an opening to permit access to the interior of said portion to permit insertion of tools for facilitating assembly of elements with said sill.
34. In a car underframe, bearings near the sides of the underframe for supporting the same on corresponding truck bearings, and a member extending between said bearings inwardly and rearwardly thereof across the underframe to accommodate draft rigging elements projecting to the rear of a straight line between said bearings.
35. In a car underframe, bearings near the sides of the underframe for supporting the same on corresponding truck bearings, and a member extending between said bearings inwardly and rearwardly thereof across the underframe to accommodate draft rigging elements projecting to the rear of a straight line between said bearings, said

member including a continuous lower tension element with its forward portion recessed for accommodating the rear end of a coupler yoke.

5 36. In a car underframe, truck engaging bearings near the sides of said underframe, and a bolster-like member between said bearings with its middle portion farther from the end of the car than its ends.

10 37. In a car underframe, draft sills, diagonal sills extending outwardly and rearwardly from the forward portion of said draft sills, a member spaced from the end of the car and inclined forwardly and outwardly from the car center and extending across said draft sills and diagonal sills between the respective ends of each of said sills.

20 38. In a car underframe, draft sills, diagonal sills extending outwardly and rearwardly from the forward portion of said draft sills, a member spaced from the end of the car and inclined forwardly and outwardly from the car center and traversing said draft sills and diagonal sills and extending beyond the latter to provide truck engaging bearings.

30 39. In an underframe casting for railway cars with dumping doors, a sill member having a vertical web and an upper horizontal flange extending inwardly and a lower horizontal flange, said upper flange having integral bosses on its lower face located beyond any portion of said lower flange to permit vertical application of door hinge elements thereto.

35 40. In a one-piece casting comprising a car underframe, draft sills, side sills, diagonal sills connecting said sills, and members extending outwardly from said diagonal sills and forming elements for engaging a bearing on a car truck.

41. In a car underframe, draft sills, side sills, diagonal sills connecting said draft and side sills, and brackets on said diagonal sills extending outwardly therefrom and forming elements for engaging bearing elements on a car truck.

45 42. In a car underframe, side sills, diagonal sills extending inwardly and longitudinally of the underframe from the ends of said side sills, and brackets extending outwardly from said diagonal sills to the side of the car and adapted to carry post supporting elements.

50 43. In a car underframe, a side sill, a diagonal sill extending inwardly from said side sill toward the end of the car, a bracket extending outwardly from said diagonal sill, an element extending longitudinally from the end of said side sill, said element and bracket uniting to form a support, and a brace for car superstructure.

55 44. In a hopper car, a side sill, a diagonal sill extending inwardly from the end of said side sill toward the car end, a bracket extending outwardly from said diagonal sill and provided with a bearing for the car truck, a projection beyond said bearing including a jacking surface, and car superstructure secured to said projection.

60 45. In a car underframe, draft sills, diagonal sills extending outwardly and rearwardly from the forward portion of said draft sills, a member spaced from the end of the car and inclined forwardly and outwardly from the car center and traversing said draft sills and diagonal sills and extending beyond the latter to provide truck engaging bearings, and car superstructure supports.

70 In testimony whereof I hereunto affix my signature this 14 day of November, 1925.

WILLIAM M. SHEEHAN.
